UNITED STATES PATENT OFFICE.

HASSEL D. ROBINSON, OF WASHINGTON, DISTRICT OF COLUMBIA.

FUEL-MIXING DEVICE.

Application filed January 7, 1927. Serial No. 159,637.

This invention relates to a fuel mixing device adapted to be mounted between a carbureter and the intake manifold of an internal combustion engine. When a carbureter has unobstructed communication with the intake manifold of a motor, the charge of fuel passing from the carbureter through the manifold contains a portion of gasoline which has not been properly atomized. It has, therefore, been proposed to place a screen between the carbureter and adjoining end of the manifold so that the free gasoline must pass through the screen which will cause it to be broken up into fine particles. This has proved satisfactory to a certain extent but it has been found that it is difficult to obtain an air-tight joint between the carbureter and intake manifold.

Therefore, one object of the invention is to provide a fuel mixing device which may be firmly secured between the carbureter and intake manifold without danger of leakage.

Another object of the invention is to provide the fuel mixer with a plurality of fuel atomizing screens spaced from each other so that particles of free gasoline which are not properly broken up by one screen will be acted upon and properly disintegrated while passing through the second screen.

Another object of the invention is to prevent danger of the screen or screens becoming detached from or slipping out of proper relation to the disk or body portion of the device.

The invention is illustrated in the accompanying drawing, wherein

Figure 1 is a view in side elevation showing one of the improved fuel mixers secured between a carbureter and adjacent end of an intake manifold;

Fig. 2 is an enlarged view showing the device principally in elevation, a facing sheet thereof being partially broken away;

Fig. 3 is a sectional view taken on the line

45 3-3 of Fig. 2;

Fig. 4 is an enlarged fragmentary sectional view of the device;

Fig. 5 is a view showing a modified form of device in elevation, and

50 Fig. 6 is a sectional view taken on the line 6-6 of Fig. 5.

The fuel mixer constituting the subject-matter of this invention is intended to be mounted between the outlet neck 1 of a carbureter 2 and adjoining end of an inlet manifold 3. The adjoining ends of the car-

bureter neck 1 and intake manifold are formed with collars 4 and 5 having openings provided therein to receive the securing bolts B and the fuel mixer conforms to the 60 contour of the collars 4 and 5 and includes a body portion or disk 6 having its end portions formed with openings 7 to receive the bolts B. It will thus be seen that, when the device is fitted between the carbureter and 65 intake manifold and the bolts inserted and tightened, it will be very firmly held in place with its opening 8 registering with the fuel passages of the carbureter and manifold. The opposed faces of the disk 6 are 70 formed with recesses 9 which extend about the borders of the opening 8 and constitute countersunk seats in which are received the marginal portions of the screens 10. The screens are preferably formed of fine wire 75 mesh and are of such size and thickness that they fit snugly in the seats 9 with their outer faces flush with the surfaces of the opposed faces of the disk, as clearly shown in Fig. 4. After the covering disks 10 have 80 been fitted into the seats 9, facing sheets 11 which are preferably formed of thin paper are applied to the opposed faces of the disk 6 and glued or otherwise secured thereto. These facing sheets conform to 85 the contour of the disk or body portion 6 and are formed with openings which register with the opening 8 and are of the same diameter. Since the openings in the facing sheets are of the same diameter as the 90 opening 8, the portions of the covering sheets bordering the openings formed therein overlap the marginal portions of the covering sheets 10, as shown in Figs. 2 and 4, and will 95 serve to securely retain the covering sheets in the seats or recesses 9. It should be further noted that since the covering sheets are countersunk in the disk or body portion 6, the facing sheets 11 will have smooth outer surfaces which will fit flat against the confronting faces of the flanges 4 and 5 of the carbureter and intake manifold. Therefore, when the bolts are tightened, the confronting faces of the flanges 4 and 5 will have 100 flat contacting engagement with the outer surfaces of the facing sheets throughout the entire areas thereof and, there will be no danger of leakage due to a tight joint not being formed. It should be further noted that the screens are prevented from moving 105 out of their seats and, therefore, cannot accidentally slip out of proper covering rela-

tion to the opening 8 and also that there will be no danger of suction causing them to be dislodged. Since the screens are held in spaced relation to each other by the portion 5 of the disk or body 6 between the seats 9, particles of free gasoline passing from the carbureter must pass through the two screens in order to enter the intake manifold and these particles of gasoline will, therefore, be 10 acted upon twice and will be broken up and a properly atomized charge of fuel insured.

In Figs. 5 and 6, there has been shown a modified form of the invention. The body portion or disk 12 is of a different configuration from that shown in Fig. 2 but is formed with bolt-receiving openings 13, corresponding to the openings 7, and with a fuel passage or openings 14, corresponding to the opening 8. About the openings 14 are 15 formed recesses or seats 15, corresponding to the seats 9, and the opposed faces of the disk 12 are covered with facing sheets 16, corresponding to the facing sheets 11. The fuel atomizing screens 17 instead of consisting 20 of flat disks or sheets are pressed to form cups, one of which is disposed in nested relation to the other, as shown in Fig. 6. Referring to this figure, it will be seen that the walls of the cup-shaped screens 17 are 25 bent outwardly to form annularly extending flanges 18 which fit into the recesses 15 and are securely held therein by the overlapping 30

portions of the facing sheets 16. By having the screens formed, as shown in Fig. 6, the device may be applied to a carbureter having a butterfly valve so disposed in the outlet neck thereof that it would be liable to 35 strike one of the screens 10 and prevented from being properly opened or closed.

Having thus described the invention, I 40 claim:

A fuel mixer comprising a body adapted to be gripped between companion portions of a carbureter and intake manifold and having opposed flat faces, said body being 45 formed with an opening constituting a fuel passage and having its opposite faces formed with recesses extending about the margins of the opening and constituting seats, gauze disks spaced from each other and covering 50 opposite ends of said opening and having their marginal portions fitting snugly into and completely filling said seats, the outer surfaces of said disks being flush with the faces of said body, and facing sheets completely covering the said faces of said body 55 and secured against the same and overlapping the portions of the gauze fitting into said seats and secured thereon, said sheets being formed with openings registering with 60 the opening in the body.

In testimony whereof I affix my signature.

HASSEL D. ROBINSON. [L. s.]
